Harold P. Donle
ATTORNEY

UNITED STATES PATENT OFFICE

HAROLD P. DONLE, OF MERIDEN, CONNECTICUT, ASSIGNOR, BY MESNE ASSIGNMENTS,
TO RADIO INVENTIONS, INC., A CORPORATION OF NEW YORK

RECTIFIER

Application filed October 4, 1926. Serial No. 139,436.

My invention relates particularly to what are commonly termed hot cathode tubes. One object is to provide a simple, reliable and efficient rectifier for use in the power supply of radio receiving sets.

In its preferred form the invention will comprise a tube containing a filamentary cathode with two anodes partially embracing said cathode. These electrodes are arranged so as to mutually cooperate for effective results. The electrodes are tied or stayed by a simple sort of truss formation so as to hold them securely in their proper relative positions. The tube is filled with some kind of ionizable gas at a low pressure.

Fig. 1 is a side view of a rectifier embodying one form of my invention.

Fig. 2 is a transverse section of the same.

Fig. 3 is a perspective view showing parts of the interior structure.

The tube 5 may be of any suitable construction and preferably contains a press 6 at the lower end in which are secured the various conducting and supporting wires.

The cathode element consists of two parts or sections, 7 and 8, each of which is in the form of an inverted V. These sections have their inner adjacent ends joined or electrically connected together and mechanically connected to the central support 9 and have conductive supports 10 and 11 for their outer ends. The center of each section is supported by a spring hook member such as 12 and 13.

The anodes 14 and 15 are trough shaped and partially embrace the two cathode elements. The cathodes and anodes are arranged so as to mutually cooperate for effective action. The anodes are supported by conductor wires 16 and 17, which for convenience in manufacture are welded to the lower ends of wires 18 and 19, which in turn are welded to the side edges of the anodes.

The anode conductors 16 and 17 are preferably sealed in the outer opposite edges of the press 6 so that they will be as far apart as possible on account of the great difference in potential which may exist between them.

To more securely hold the parts in their proper relative positions, I provide a sort of truss consisting of an insulator preferably

in the form of a glass bead or bar 20 in which are embedded ends of wires 21, 22, 23, 24 and 25. Wire 21 is mechanically secured to the support 9 by the stay 26 which is welded to both of them. The hook wires 12 and 13 are welded to the upper ends of the wires 22 and 23 and should be sufficiently light and resilient to provide a slight tension on the filament without straining it. The upper ends of the wires 24 and 25 are bent over and welded to the upper ends of the side wires 18 and 19 near the upper ends of the anodes which thus brace the outer ends of the anodes.

Fig. 3 shows the electrodes separated from the other parts of the truss-like structure.

The electrodes are preferably enveloped in an atmosphere of some ionizable gas which will properly coat with the filament to produce the effect of increased emission without injuring the filament. Such a combination I have found in the use of a thoriated molybdenum cathode in an atmosphere of iodine. Only a small amount of iodine is necessary or desirable. I have found a pressure of from .01 to .001 millimeters of mercury satisfactory. The conditions should produce partial or non-cumulative ionization without glow. Such a combination operates at a comparatively low temperature with efficiency. The anodes may be of nickel.

It should be understood, however, that I consider that other highly refractory filaments may be used such as tungsten. So also other rare earth oxide coatings may be used. I also consider that other gases may be employed to produce somewhat similar results.

I claim:

1. A full wave rectifier comprising a tube having a press with five supporting wires sealed therein, a filament having its ends secured to two of said wires and folded into two parts with the center secured to another of said wires, channel-like anode elements secured to the remaining two wires and partially embracing said filament, and a supplemental support consisting of a glass bead with five wires sealed therein, one of said wires being secured to the wire which supports the center of the filament, two other of said wires having spring arms for supporting

the intermediate portions of the filament, and the remaining wires being secured to the outer ends of the anodes.

2. A full wave rectifier comprising a tube 6 having an internal press at one end with five supporting wires sealed therein, a cathode filament consisting of two inverted V-shaped sections connected together at their inner ends, said inner ends being supported by one 10 of said wires and having their outer ends electrically connected to and mechanically supported by two of the other supporting wires, an insulating member supported by the first mentioned wire, two wires supported by said 15 insulating member and in turn supporting the mid-points of the two cathode sections, two anode structures mechanically and electrically supported by the remaining two supporting wires which are sealed in the press 20 and supplemental bracing wires secured to said insulating member and connected to the outer ends of the anode structures, each of said anode structures including at least two plate portions spaced apart from and substantially parallel with the central planes of 25 the respective cathode sections.

3. A full wave rectifier comprising a tube having an internal press at one end with at least four supporting wires sealed therein, 30 two anode structures mechanically and electrically supported by two of said supporting wires, an insulating member, bracing wires secured to said insulating member and connected to the outer ends of the anode structures, a cathode filament consisting of two inverted V-shaped sections connected together at their inner ends and having their outer ends electrically connected to and mechanically supported by two of the other supporting 35 wires, two wires extending from said insulating member and supporting the mid-points of the two cathode sections, each of said anode structures including at least two plate portions spaced apart from and substantially parallel with the central planes of the respective cathode sections, and means of mechanical connection and support between the insulating member and the inner ends of the cathode sections.

4. A full wave rectifier comprising an envelope having a press at one end, five supporting wires sealed in said press, four of said wires constituting conductors, an insulator supported by the fifth wire, two inverted V-shaped filamentary cathode sections suspended from said insulator, one end of each section being held in fixed position by means including said fifth wire, the other end of each section being connected to one of said conductors, a flat sided anode embracing each cathode section and supported by one of the remaining conductors, and bracing means connecting the anodes and said insulator.

5. A full wave rectifier comprising an envelope having a press at one end, four con-

ductors and a support all carried by said press, an anode supported by each of two of said conductors, each anode having two parallel spaced-apart side members connected at adjacent edges, an insulating spacer, bracing means of mechanical connection between said spacer and said anodes, two filamentary cathode sections of inverted V-shape electrically connected together at one end of each and mechanically supported between the sections by said support, the other ends of the filament sections being electrically connected to the remaining two conductors carried by the press, and tensioning supporting means for the mid-points of the two filament sections carried by said insulating spacer, each filament section being supported substantially in the center of an anode between its spaced apart side members.
